UNITED STATES PATENT OFFICE

PHILIP C. DE BRUYNE, OF ST. CHARLES, ILLINOIS, ASSIGNOR TO MOLINE MALLEABLE IRON COMPANY, OF ST. CHARLES, ILLINOIS, A CORPORATION OF ILLINOIS

METHOD OF CASTING AND REPAIRING CHAIN

Application filed November 10, 1930. Serial No. 494,645.

My invention relates to a method of casting or forming or repairing chain or chain links, and particularly to the casting or repairing of chain consisting of a plurality of 5 inter-penetrating links, all of which links shall be solid and without joint or seam. Another object is the provision of a method for casting connecting links to join adjacent preformed links. Another object is the 10 provision of improved means for forming the molds of said connecting or inter-penetrating links and the inter-penetrating parts thereof. Other objects will appear from time to time in the course of the specification and claims.

I illustrate my invention more or less diagrammatically in the accompanying drawings, wherein—

Figure 1 is a plan view of the pattern;

20 Figure 2 is a section on the line 2—2 of Figure 1;

Figure 3 is a section showing the pattern in the cope;

25 Figure 4 is a plan view illustrating the drag with links in position;

Figure 5 is a section on the line 5—5 of Figure 4 with the mold ready for casting;

Figure 6 is a section on the line 6—6 of Figure 5;

30 Figure 7 is a section on the line 7—7 of Figure 2;

Figure 8 illustrates a core employed;

Figure 9 is a plan view of variant form of pattern;

35 Figure 10 is a section on the line 10—10 of Figure 9;

Figure 11 is a plan view illustrating drag with chains in position and ready for casting; and

40 Figure 12 is a section on the line 12—12 of Figure 11, with the mold ready for casting.

Like parts are indicated by like symbols throughout the specification and drawings.

45 Referring to the forms of Figure 1 and following, A generally indicates a pattern board which may be of aluminum or any suitable metal or any other suitable material and which has formed on each face thereof a plurality of half link molds. A¹ indicates

horizontal links and A² indicates inter-penetrating vertically positioned links. A³ indicates the patterns adapted to form gates for pouring, such gates being indicated in communication with adjacent horizontal link 55 forms A¹, as at A⁴, A⁵. The gates formed in the below described cope by the members A³ are preferably of sufficient capacity to hold a supply of molten metal which may flow into the link forming mold impressions 60 to take up shrinkage of the link and to prevent an undersized and porous link.

Referring to Figure 3, the pattern may be positioned upon any suitable base or mold board B, and may receive, upon the board 65 A, the cope indicated as B¹ which may be positioned, for example by the lugs A⁶ which pass through apertures in the outer projections B² from the end walls of the cope. B³ indicates sand which may be rammed into the cope and against and about the pattern to receive its form or impression. When the cope has been rammed, it may be inverted and the pattern withdrawn. The same process is followed with the drag B⁴, 75 the pattern being inverted and the drag applied to the opposite side, rammed, inverted and then the pattern withdrawn.

It will be understood that in my process the links filling the impressions A¹ are 80 poured simultaneously, while the links conforming to the impressions A² are preformed and are then provided with supplemental molds or cores which complete the impressions or forms necessary for the pouring of 85 the links A¹. For example I may provide cores D, as shown in detail in Figure 8. The exterior surface D¹ of each such core may conform to the interior of one end or of an intermediate portion of the cavity 90 of one of the preformed or precast links C¹ but due to the fact that the adjacent surfaces of the link and core are both arcuate (see Figs. 5 and 6), the link and cores may be rockingly moved with respect to 95 each other while fulcruming upon the line of contact between the elements. The projecting ends of the cores conform to the impression made by the portion A⁷ of the pattern. Thus when a preformed link is pro- 100

vided at each end with one of the cores D, the link C¹ and its cores D being positioned in the corresponding cavities formed by the pattern, the cores D are in proper position 5 to communicate with the apertures A⁷ which they complete to form a cavity which, when filled with metal, will produce one of the desired seamless or jointless inter-penetrating links.

10 In preparing for the casting, the cores D may be threaded in the preformed links, and links and cores are then positioned in the corresponding cavity A². After the pre-formed links have been positioned, with 15 their cores, in the drag, the cope may then be lowered in place to form the completed mold shown in Figure 5. It will be understood that the interior apertures of the cores D are of proper size and position to form 20 a complete and regular chain link. Metal may then be poured through the gates A³.

The cores D may be formed in any desired core box and may be of sand and oil. They are baked in any suitable manner in 25 order to reach a predetermined range of hardness, being sufficiently hard for ready handling. After the intermediate links have been cured and have set the entire mold, including the cores D, may be broken to 30 free the completed length of chain.

Clearly I may pour a greater or a lesser number of links and I do not wish to be limited to the precise arrangement of the links in the mold, except so far as I specifically limit myself by my claims. For 35 example, it may frequently be necessary to repair a length of chain by replacing or adding a single length. Or it may be desired to join two shorter links of chain in 40 order to form a longer length. In such case it is desirable to provide a mold adapted to receive the terminal links of preformed chain, which terminal links may be joined by a single link impression. Referring for 45 example to Figures 9 to 12, I illustrate a pattern board E of any suitable material which has formed on each face thereof a complete half link impression E¹ lying in the general plane of the board, and impressions E² of the ends of inter-penetrating links, each such impression E² having associated therewith the half impressions E³ to conform to one of the sleeves or cores D. A single gate impression E⁴ is employed.

50 In employing this pattern, a drag G and a cope G¹ are employed, as above described in connection with the form of Figures 1 and following. Preformed links G² project through the walls of drag and cope into the 55 apertures E². Threaded into these links, at the inner end of the aperture of each link, is one of the cores D conforming to the form E³ of the pattern. Thereby an impression for a complete link is formed and 60 when metal is poured through the gate E⁴,

it fills the impression made by the portions E¹ of the pattern and flows also through the interior apertures of the cores D. Thus a single link may be poured to repair a chain or to join two chain sections.

70 I claim:

1. The process of casting chain which includes forming a plurality of inter-penetrating link mold impressions, pre-forming individual links, forming apertured cores, threading said cores through the link apertures of performed links, positioning pre-formed links, with the cores therein, in alternate link impressions, and positioning the cores, independently of variations in the 75 position of pre-formed links, to complete the link mold impressions which inter-penetrate the impressions in which the pre-formed links are positioned, pouring said inter-penetrating links, and breaking the mold 80 and cores to free the completed chain.

2. The process of joining adjacent pre-formed chain links which includes positioning said links in mold apertures, providing an inter-penetrating link forming mold 85 aperture therebetween, and independently positioning cores within the apertures of each of said pre-formed links, and in conformity to said interpenetrating link forming mold aperture, pouring molten metal 90 into said mold apertures, and breaking the mold and cores to free the completed chain.

3. The process of joining adjacent pre-formed chain links which includes positioning said links in mold apertures, providing inter-penetrating link forming mold apertures therebetween, independently positioning cores within the apertures of each of said pre-formed links, and in conformity to 100 said inter-penetrating link forming mold apertures, pouring molten metal into said mold apertures, maintaining an additional body of molten metal in communication with said mold apertures, during the pouring and setting of the links so formed, and breaking 105 the mold and cores to free the completed chain.

Signed at St. Charles, county of Kane and State of Illinois, this 3rd day of Nov. 1930.

115 PHILIP C. DE BRUYNE.
